UNITED STATES PATENT OFFICE

JOSEPH KAUFMAN, OF NEW YORK, N. Y., ASSIGNOR TO AMERICAN SAFETY RAZOR CORPORATION, OF NEW YORK, N. Y., A CORPORATION OF VIRGINIA

RAZOR-BLADE-RETAINING ELEMENT

Application filed April 22, 1926. Serial No. 103,677.

My present invention relates generally to razor blades and to the manner of their association with a razor, and has particular reference to blades of the type which are used in connection with safety razors of the "Ever-Ready" type.

In razors of this type, it is customary to utilize a blade in connection with a holding device wherein certain guides and stops are provided for removably associating the blade with the holder in predetermined positions.

More particularly, in the holder of the type to which this invention has particular reference, it is customary to provide stops at the forward end of the holder against which the forward or cutting edge of the blade may rest, and to provide suitable means for exerting a forward pressure upon the rear edge of the blade so as to hold the forward edge firmly against the stops. With this purpose in view, it has been customary to provide the rear edge of the blade with a retaining or reinforcing portion against which the forwardly pressing means may operate.

In view of the foregoing premises, it is one object of the present invention to provide a retaining or reinforcing portion of the character referred to which will be removably applicable to an edge of a blade, whereby the necessity for providing each individual blade with such a portion is eliminated, and whereby a single one of such reinforcing portions may be selectively or successively utilized with any desired number of blades. In this manner, I attain the result of being able to use the retainer with a sharpened edge so that the employment of this type of retainer does not prevent the practical employment of a blade sharpened on its opposite edges.

Another object of my invention is to provide a retaining or reinforcing portion of this character which does not contact with the effective portion of a cutting edge, where it is associated with a cutting edge. In accordance with this phase of the invention, it is possible for me to utilize double edged blades of the so-called "Gillette" type with blade holders or razors of the type heretofore known as the "Ever-Ready" type and more specifically described hereinabove.

Bearing this phase of the invention in mind, as well as its employment with the type of razor referred to, a preferred embodiment of the invention contemplates the contacting of the retaining or reinforcing portion with only the extreme ends of an edge of the blade, these extreme ends being normally unavailable for cutting purposes even when this edge is employed for shaving purposes because of the engagement of these ends with the usual stops provided on the blade holder.

According to another phase of the invention, I am enabled to facilitate shipment of blades, because I may apply the removable portion to the cutting edge of any desired blade or blades and therefore protect said edge during its shipment.

Regardless of the particular embodiment, it is a feature of the invention to provide the removable reinforcing portion with means for permitting association thereof with the blade in a predetermined positional relation, whereby the rear portion of the assembled blade is provided with a predetermined thickness, and whereby the length from front to rear of the assembled blade is of a predetermined magnitude, thereby adapting the assembled blade for unimpaired use with the holders or razors of well-known construction.

Where the reinforcing portion is designed for interchangeable use with double-edged blades, so that only one edge is available for cutting purposes while the other edge is sheathed and protected, it is a feature of the invention to provide the reinforcing portion with means for enclosing said protected edge within the outermost contour of the applied sheath, thereby permitting utilization of the assembled blades in a customary manner without causing damage, or even contact, to the protected edge.

For the achievement of the foregoing objects and such other objects as may herein-after appear or be pointed out, I have illustrated several embodiments of the invention in the accompanying drawings, wherein—

Figure 1 shows my adaptor applied to a double edge blade, and

Figure 2 shows in perspective on an enlarged scale one side of the adaptor.

In Figure 1 of the drawing, I have illustrated the employment of a retaining member 18 which serves as an adaptor for the blade 14 to permit said blade with the adaptor to serve with that type of razor in which the blade is engaged at the rear and advanced so as to bring the active shaving edge against the front stops of such type razor. In this embodiment, the blade 14 is of the double edge type and is provided along its opposite side edges with spaced notches 29. Two such notches are on each side edge and the notches are symmetrically positioned with reference to the opposed shaving edges for reasons that will be understood.

The adaptor or retaining member 18 is in the form of a member bent midway of its length to provide two opposed walls and a channel therebetween within which channel one edge of the blade is received and protected as well as reinforced. These slots begin at a point adjacent the two walls of the adaptor join and extend entirely through the width of the walls and are open at the lower ends. There are thus provided two tongue portions or fingers 30, which are disconnected from the wall from which they are formed except at the rear. These fingers 30 extend generally in the plane of the wall and are provided at the free ends with the downwardly and inwardly directed tongue elements 31, all as shown clearly in Fig. 6. The tongues 30 are imparted a certain resilience which tends to make the tongue 31 extend across the gap between the opposite sides of the retaining portion. When the blade is inserted, each tongue 30 must be slightly distorted to permit passage of the blade past the tabs 31; and after the blade has been inserted a predetermined amount, the resilience of each tongue will cause the tab 31 to engage with a notch 29 and thereby positively engage and hold the blade in predetermined position. This engagement will prevent the interposed cutting edge of the blade from contacting with the rear bent-over edge of the retaining member.

In accordance with this embodiment, it will be obvious that the blade may be utilized, if desirable, with a holder or razor of a different type wherein stops 12 are absent, and wherein other means have been provided for predetermined and positioning the association of the blade with the holder.

I claim:—

An adaptor for a blade of the wafer type comprising two super-imposed members associated together along one end and free of each other at their opposite end, fingers extending from a point adjacent the end where the members are joined and extending forwardly in the plane of one of the members, said fingers each having an inwardly directed element as its terminal end, said inwardly di-

rected elements being substantially in the plane of the side edges of the adaptor.

In witness whereof, I have hereunto signed my name this 9th day of April, 1926.

JOSEPH KAUFMAN.
